UNITED STATES PATENT OFFICE.

EDWIN P. MCALLISTER, OF CLIFTON HEIGHTS, PENNSYLVANIA.

PUNCTURE-REPAIR NEEDLE.

SPECIFICATION forming part of Letters Patent No. 606,570, dated June 28, 1898.

Application filed July 22, 1897. Serial No. 645,518. (No model.)

To all whom it may concern:

Be it known that I, EDWIN P. MCALLISTER, a citizen of the United States, and a resident of Clifton Heights, Delaware county, Pennsylvania, have invented certain Improvements in Puncture-Repair Needles, of which the following is a specification.

The object of my invention is to provide a simple and efficient device for effecting the plugging or repair of punctures or incisions in flexible tubes, such as pneumatic tires of bicycles, rubber hose, or other flexible and puncturable tubular or hollow objects intended for holding or conveying air, water, or other fluid under pressure. This object I attain in the manner hereinafter set forth, reference being had to the accompanying drawings, in which—

Figure 1 is a perspective view of a puncture-repair instrument constructed in accordance with my invention. Figs. 2 and 3 are views illustrating the manner in which the instrument is intended to be used. Fig. 4 is a view illustrating the nature of the plug left in the hole after the instrument has been withdrawn. Fig. 5 is a sectional plan view of part of the instrument. Fig. 6 is a side view of the end of the same, and Fig. 7 is a side view illustrating a modification.

1 represents a needle or stem preferably cylindrical as to its body and having at the outer end a handle 2, said needle being flattened on each side at its inner end and having at this end a V-shaped notch or recess 3, Fig. 6.

To the needle 1, some distance from the inner end of the same, is suitably secured a knob or collar 4, and upon the main stem of the needle 1 is mounted, so as to be free to slide, a sleeve 5, having lateral projections or wings 6, said sleeve having formed in it at one side of the central opening which receives the stem of the needle 1 a longitudinal slot or groove 7, while in the inner end of the sleeve is formed a surface notch or recess 9, as shown in Fig. 1.

Projecting from one side of the stem of the needle 1 is a lug or pin 10, which, when the sleeve 5 is retracted, serves to retain said sleeve in the retracted position, the lug projecting over the end of the sleeve and rest-

ing in the notch 9, and the sleeve being pressed toward the lug by means of a coiled spring 11, interposed between said sleeve and the end of the handle 2, so that the end of the sleeve 55 is maintained firmly in contact with the lug and accidental turning of the sleeve is prevented by the engagement of said lug with the notch 9.

In order to repair a puncture, ordinary rubber bands are employed, these bands being held in a stretched condition between the notched inner end of the needle 1 and the wings of the sleeve 5, the degree of attenuation of the band being governed by the circumstances of the particular case and the character of the band employed. For instance, a band may extend directly from the forked inner end of the needle to one of the wings of the sleeve 5 with a minimum amount of stretch, 70 or one loop, a band may be passed over one wing of the sleeve 5, the central portion of the band then passed through the fork of the needle, and the other loop of the band applied to the opposite wing of the sleeve 5, or where 75 a further degree of attenuation is desired one loop of the band may be applied to the forked inner end of the needle, the band then passed down around one of the wings 6, thence backward to and through the fork of the needle, 80 and thence down to the other wing of said sleeve, or a still further degree of attenuation may be effected by applying one loop of the band to one of the wings 6, then passing the band through the forked inner end 85 of the needle, thence down to and around the other wing 6, thence back to and through the fork of the needle, and thence down to the wing 6, to which the first end has been applied. After a sufficient number of bands have been 90 applied in either of these ways to effect the desired closure of the puncture or other opening the bands are liberally coated with cement and are then thrust by means of the needle through the puncture or other opening 95 in the tube, as shown in Fig. 2. The sleeve 5 is then partially turned on the stem of the needle 1, so as to bring its slot 7 into line with the lug 10, whereupon the resiliency of the bands will immediately cause the sleeve 100 5 to move forwardly on the stem of the needle until its movement is arrested by the

knob 4, the position of the latter in respect to the outer surface of the tube indicating to the user the extent to which the rubber bands have been inserted into the tube and providing for a uniform contraction of each band on the release of the sleeve 5 from the retaining control of the lug 10. The bands having been inserted in this way and permitted to expand after insertion, the outer ends of the bands are removed from the wings 6 of the sleeve 5 and the needle is withdrawn, the tapered shape of the inserted portion of the needle facilitating this withdrawal and the V-shaped notch or fork formed in the inner end of the needle insuring the clean withdrawal of the same from the inner ends of the bands and preventing the drawing up of said inner ends toward the tube. As the needle is withdrawn, the bands, owing to their resiliency, close in upon each other, and the puncture, which has been expanded by insertion of the needle, resumes its former dimensions, thus forcing the cemented bands closely together and effectually plugging the opening, as shown in Fig. 4. The outer projecting portions of the band may be then cut off, and for additional security cement may be spread over the cut ends of the bands.

By means of the instrument above described I am enabled to effect the ready and thorough repair of punctures varying in size from that produced by a pin or tack to a knife-slit half an inch long or an opening three-eighths of an inch in diameter, there being a large plug of cemented bands on the inside of the tube and the plug being so tight as to effectually resist heavy internal pressure whether of air, water, or other fluid.

While I prefer in all cases to construct the instrument in the manner shown in the drawings, various modifications of the same are possible within the scope of my invention. For instance, instead of providing the sleeve 5 with a longitudinal slot or groove for the passage of a fixed lug on the stem of the needle 1 the sleeve may be retained in its retracted position by means of a pin 12, passing through a transverse opening in said stem, as shown in Fig. 7, this pin being withdrawn when it is desired to release the sleeve, and in this case also the spring 11 may be omitted. The sleeve 5 may also have but one projecting wing instead of two, and the stop knob or collar 4 may be adjustable on the stem of the needle, if desired, a set-screw 13, such as shown in Fig. 1, or other equivalent means being employed to secure the knob in position after adjustment.

Having thus described my invention, I

claim and desire to secure by Letters Patent—

1. A puncture-repair needle comprising a stem constructed at the inner end for entering the puncture in the tube and having, some distance from said inner end, a stop knob or collar, in combination with a winged sleeve adapted to slide on the stem of the needle, and means for retaining said winged sleeve in its retracted position.

2. A puncture-repair needle consisting of a stem having a flattened and notched inner end, a stop knob or collar some distance therefrom, a winged sleeve free to slide on said stem, and provision for retaining said winged sleeve in its retracted position.

3. A puncture-repair needle consisting of a stem constructed at the inner end for entering the puncture in the tube and for receiving and retaining a rubber band or bands, a winged sleeve free to slide on said stem and having a longitudinal slot or groove therethrough, and a lug or pin projecting from the stem and serving by engagement with the inner end of the sleeve to retain the same in its retracted position, or, when brought into line with the groove, permitting the forward movement of the sleeve.

4. A puncture-repair needle consisting of a stem constructed at the inner end for entering the puncture in the tube, and for receiving and retaining a rubber band or bands, a winged sleeve free to slide on said stem and having a longitudinal slot or groove therethrough, and a notch in its inner end, and a pin or lug projecting from the stem and adapted to occupy the notch in the sleeve when the same is retracted, and to permit the forward movement of the sleeve when its slot or groove is brought into line with the pin.

5. A puncture-repair needle consisting of a stem constructed at the inner end for entering the puncture in the tube and for the reception and retention of a rubber band or bands, a winged sleeve free to slide on said stem and having a longitudinal slot or groove therethrough, a pin or lug projecting from said stem and serving by its contact with the inner end of the sleeve to retain the same in its retracted position, and a spring acting upon said sleeve and serving to press the same against said lug or pin.

In testimony whereof I have signed my name to this specification in the presence of two subscribing witnesses.

EDWIN P. McALLISTER.
